UNITED STATES PATENT OFFICE.

WALTER S. EDMANDS, OF NEWTON, AND CHARLES A. HOYT, OF BOSTON, MASSACHUSETTS, ASSIGNORS, BY DIRECT AND MESNE ASSIGNMENTS, TO EDWARD T. EDMANDS, OF NEWTON, MASSACHUSETTS, AND JUNE HOYT.

ELECTRIC BAKER FOR SURGICAL PURPOSES.

SPECIFICATION forming part of Letters Patent No. 775,105, dated November 15, 1904.

Application filed December 17, 1902, Serial No. 135,600. (No model.)

To all whom it may concern:

Be it known that we, WALTER S. EDMANDS, residing at Newton, county of Middlesex, and CHARLES A. HOYT, residing at Boston, county 5 of Suffolk, State of Massachusetts, citizens of the United States, have invented a certain new and useful Improvement in Electric Bakers for Surgical Purposes, of which the following is a specification, reference being had therein

10 to the accompanying drawings.

In the treatment of rheumatism, inflamed or stiff joints, water in the joints, bruises, and certain other classes of cases the part of the human body which is affected is sometimes 15 subjected to heat for the purpose of inducing or increasing circulation in the said part, stimulating secretions, occasioning or promoting absorption, or otherwise securing a return to normal functions and conditions, and there- 20 by bringing about relief or a cure.

The invention relates to apparatus for applying heat for the purposes stated; and the invention consists in a surgical heater or baker of the improved construction hereinafter 25 described and claimed, in which the effect of the heat is aided and enhanced by causing the heat to be applied and to act in the presence of strong and intense light, the heat and light both emanating from bodies which are em- 30 braced in an electric circuit and are rendered incandescent by the closing of such circuit. The advantages of causing the heat to act in the presence of strong light are that by the action of heat and light combined greater 35 penetration of the heat at a given temperature is secured than where heat is applied without light, enabling the desired results to be attained at a lower temperature than otherwise would be effectual and also enabling better 40 results to be attained than heretofore.

The invention provides a compact and simple apparatus adapted for handy and convenient application to any part of the body.

The accompanying drawings illustrate an 45 embodiment of our invention.

In the said drawings, Figure 1 shows in plan with the cover-sheets and lining removed an

apparatus embodying the invention. Fig. 2 shows the said apparatus in side elevation with the cover-sheets and lining in place. Fig. 3 50 shows in side elevation the switch, hereinafter described, by means of which the action of the apparatus is controlled. The cover of the working parts of the switch is omitted in order to show the said working parts. Fig. 4 55 shows in plan the switch which is represented in Fig. 3. Fig. 5 is an elevation looking from the left-hand side in Fig. 3.

Our apparatus has a sectional saddle-shaped frame, the curved parts or sections of the said 60 frame being movably connected with each other, so as to enable them to be adjusted relatively to each other to suit the portion of the human body which is required to be treated with the aid of the apparatus. The construction 65 and the precise means of connecting and adjusting the parts or sections of the apparatus may vary more or less in practice.

In Figs. 1 and 2 the two curved segmental sections 12 12 are connected together pivotally 70 at their upper ends by means of the rod 13 and the pivotal screws 14 14, the screw-threaded inner ends of the said screws entering screw-threaded holes that are tapped in the opposite ends of said rod 13 lengthwise of the rod. 75 The sections 12 12 may be swung relative to each other upon their pivotal connections to thereby expand or contract the apparatus to the required width. Each section is shown composed of two side bars 121 121, having the 80 heat and light producing bodies applied thereto, and tying and spacing rods 122 122, by which the lower ends of said side bars are connected and held at the proper distance apart. Each of the rods 122 122 fits between 85 the opposite inner faces of the side bars 121 121 of the section, and the respective ends of said rods are secured to the said side bars by screws 123 123, passing inwardly through holes in the side bars and entering screw-threaded holes which are tapped in the ends of the rods. The side bars are composed each 90 of an inner strip of brass or other suitable material 124 and an outer strip 125 of vulcan-

ized fiber or the like, although we do not limit ourselves in these respects in the construction of the sections. The upper ends of the side bars overlap. The opposite ends of the rod 5 18 make contact with the inner sides of the innermost strips at the joints at the opposite ends of the apparatus, and thereby hold the upper ends of all the side bars properly spaced apart, the pivotal screws 14 14, having plain 10 barrels 141, occupying the holes that are made through the overlapping portions of the side bars of the opposite sections. The means and manner of keeping the sections in their position of adjustment may vary in practice. 15 Herein we have shown a convenient form of latch comprising a spring-strip 16, which is secured at one end, as by a screw or screws 161 161, to the outer side of one of the side bars, the said spring-strip 16 being provided 20 with a pin, as 162, which works within a hole, as 163, in the said side bar, the adjacent overlapping portion of the other side bar having a circular series of holes, as 164 164, &c., to receive the engaging end of the said pin. 25 For convenience in moving the spring-strip 16 in manipulating the latching device the said spring-strip is furnished with a knob or head, as 165.

The manner of arranging the heat and light 30 producing bodies upon the respective sections of the apparatus shown in Figs. 1 and 2 may vary in different cases. Herein a simple arrangement of the said bodies is shown. Thus a series of sockets 61 61 is mounted upon the 35 inner face of each side bar 121 of each section, and to the said sockets are applied incandescent electric-light lamps 62 62, extending in the direction of the length of the apparatus, the said lamps being herein of the elongated cylindrical form sometimes termed 40 "candles" or "bung-hole" lamps and overlapping with one another for a portion of their length. The lamps 62 62 are connected electrically in a suitable circuit or circuits for the 45 purpose of enabling the degree of heat and light to be varied when required. The said lamps are provided with electrical connections arranged and contrived to permit a part or the whole of the entire number of lamps to be 50 rendered operative at one time, as may be required. Thus the lamps of the side bars at one side of the apparatus constitute one group and those of the side bars at the other side of the apparatus constitute the second group, 55 each group being embraced in a separate circuit or branch circuit. Switch connections are provided whereby to enable either or both of the said groups to be turned on or off in use, as desired. The switch connections may 60 vary in practice in some cases, although we prefer to employ a single switch of a construction enabling the different groups of the lamps to be turned on successively by successive movements of the handle or button of said 65 switch and to be turned off similarly. A

switch of suitable character is illustrated in Figs. 3, 4, and 5 of the drawings. In the said figures, 181 is a binding-post for one line-wire 7 of the electric circuit, and 182 183 are binding-posts for the branch wires 71 72, leading, 70 respectively, to the two groups into which the lamps are divided. Each of the said binding-posts has a pair of yielding contact blades or lips, as 184 184, between which a contact-piece carried by the moving member 185 of the switch is adapted to enter. The said moving member is centrally located and is provided with a button or handle, as 186, for enabling the same to be turned by hand. The movable switch member 185 is provided with 80 a bottom series of contact-points or arms, as 187^a 187^b, &c., and a top series 188^a 188^b, &c., and has in addition a single contact-point or arm 189. The contact-points or arms 187 are located and rotated in one plane, which latter 85 corresponds with the plane of the contact-blades 184, carried by the binding-post 181 for the line-wire 7. The series of contact-points or arms 188 are located in a second plane, which latter corresponds with that of the contact-blades or arms 184 of the binding-post 182, pertaining to one group of lamps. The single arm or contact-point 189 is in a third plane, 90 which corresponds with that of the contact-blades or arms 184, carried by the binding-post 183, pertaining to the second group of lamps. The various contact-points or arms 187, 188, and 189 on the moving switch member are so disposed upon the said switch member that in one position of the latter all of the 95 contact-points or arms carried thereby are out of contact with the contact-points or arms of the three binding-posts. An advance of the movable member of the switch into a given position would place one of the contact-points 100 thereof, as 187^a, in engagement with the contact-blades of the binding-post 181 for the line-wire 7, and one of the contact-points, 188^a, of the said moving switch member in engagement with the contact-blades of the binding-post 182 for the branch wire 71, leading to one 105 of the groups of lamps, thereby placing the said group in circuit. A second advance of the moving switch member would place a second contact-point, as 187^b, on the same in engagement with the contact-blades of the binding-post 181 for the line-wire 7, another of the contact-points, as 188^b, in engagement with the contact-blades of the binding-post 182 for the said group of lamps, and also the 110 single contact-point 189 of the said moving switch member in engagement with the contact-blades of the binding-post 183 for the branch wire 72, leading to the other group of lamps. In this position of the moving switch 115 member both groups of lamps will be turned on. Another advance of the moving switch member will move the arm or contact-point 189 out of engagement with the contact-blades 184 of the binding-post 183 for the wire 72, lead- 120

125 130

ing to the second group of lamps, thereby turning off the said group, while the first group will still remain turned on through the engagement of one of the contact-points, 188^c, 5 of the moving switch member with the contact-blades of the binding-post 182 of the wire 71, pertaining to the said first group of lamps, and the engagement of one of the contact-points, 187^c, with the contact-blades of the 10 binding-post 181, pertaining to the line-wire 7. Another advance of the moving switch member will carry the same into a position in which all of the contact-points thereof are 15 out of engagement with the various contact-blades of the different binding-posts, and in this position of the moving switch member all of the lamps will be turned off. Inasmuch as switches of this type are known in the art, being used in connection with electroliers, 20 &c., it is unnecessary to present the construction of the switch in detail or to go further into the mode of operation of the same. The particulars of construction and of operation are not material to the present invention and 25 may be as heretofore or as may be preferred.

Each section is provided with a cover-sheet 17, inclosing the space between the two side bars of such section. The said cover-sheets 17, if desired, may be lined with white asbestos, as at 171, to reflect the heat and light 30 inwardly, while the space between the upper ends of the opposite cover-sheets, if desired, is closed by a section of flexible asbestos cloth or other suitable material, as at 172, which 35 may be constituted by a portion of the said lining material. In use a suitable covering-cloth, of asbestos or the like, usually is thrown over the apparatus and the part of the human body under treatment therein, although in 40 some uses of the apparatus the cover is dispensed with in practice.

The apparatus is suspended from above by wires or the like, two such wires being indicated in part at 18 18, the same being connected with the tie-rod 13 and extending upwardly therefrom. By means of said wires 45 the apparatus may be raised or lowered, as required, and is or may be supported thereby

when not in use. By reason of supporting the apparatus from above through the agency 50 of a suspensory support the use of stands or the like is rendered unnecessary. Stands are inconvenient at times and are more or less trouble to place where required for adjusting an apparatus of this class to the patient who is treated. When the apparatus is 55 hung from above by means of a suspensory cord or wire, it admits of readily being raised or lowered and of being swung or shifted in any direction, while in being applied it may 60 be placed in any position made necessary by the part of the human body which is required to undergo treatment or the conditions of use.

We claim as our invention—

1. The improved surgical baker comprising 65 the opposite side sections hinged together at the upper ends thereof and adjustable toward and from each other to vary the distance between them, and provided with means of holding the same in their position of adjustment. 70

2. The improved surgical baker comprising the opposite side sections hinged together at the upper ends thereof and adjustable toward and from each other to vary the distance between them, and provided with means of holding 75 the same in their position of adjustment, of the overhead suspensory support.

3. The improved surgical baker comprising the opposite side sections hinged together at the upper ends thereof and adjustable toward 80 and from each other about their hinged connections, provided with means of securing the said sections in their position of adjustment, having the electric elements electrically connected in groups comprising each a plurality 85 of such elements, and provided with switch connections whereby the groups may be placed in and out of operation singly and jointly as described.

In testimony whereof we affix our signatures 90 in presence of two witnesses.

WALTER S. EDMANDS.
